UNITED STATES PATENT OFFICE.

VICTORINO MARTINEZ, OF HABANA, CUBA.

ELECTRIC-LAMP HOLDER.

1,343,573.

Specification of Letters Patent. Patented June 15, 1920.

Application filed June 4, 1917. Serial No. 172,775.

To all whom it may concern:

Be it known that I, VICTORINO MARTINEZ, citizen of the Republic of Cuba, residing at Habana, have invented certain new and useful Improvements in Electric-Lamp Holders, of which the following is a full, clear, and exact specification.

This invention relates to an improved form of electric bulb socket, together with a new type of switch therefor.

Referring to the accompanying drawings:

Figure 1 is an end elevation of a socket constructed in accordance with my invention.

5 Fig. 2 is a side elevation thereof.

Fig. 3 is a vertical section taken along line 3-3 of Fig. 2.

Fig. 4 is a vertical section taken along line 4-4 of Fig. 1 showing the circuit closed.

10 Fig. 5 is a view similar to Fig. 4, but showing the circuit open.

Fig. 6 is a section taken along the line 6-6 of Fig. 2.

Fig. 7 illustrates certain details of my insulating and contact members.

Fig. 8 shows the second of the contact members.

Fig. 9 illustrates the switch included in my socket.

0 Referring more particularly to the reference letters on the views, it will be seen that 1 designates the outer shell preferably constructed of a non-conducting material such as wood, such shell being provided adjacent 5 its lower end with a metallic ring 1' and being further formed with a restricted neck opening at its upper end, such as 2 provided with a gasket 3 retained in applied position by means of the screw 4.

0 The inner face of the lower end of the shell 1 is cut with screw threads 5, adapted to engage and retain in applied position the conventional metallic liner 6. A porcelain insulator, or one which may be constructed 5 of other suitable material, formed in two halves 7 and 7' is positioned in the upper part of the shell 1, the half 7' being provided with a cutaway portion 8 and being further provided with a transverse opening 9 which continues to a certain depth into the second half, which opening 9 is adapted to house a screw 10 serving the double purpose of securing the bare end of the wire 11 as well as holding the two halves 7 and 7' firmly together.

A longitudinal opening 13 extends

through the entire length of the half 7 which opening is adapted to inclose the stem 12 of the contact member 14 which is connected to the wire 15 by means of the reduced end portion 12'.

A contact plate 16 is provided with a stem with an enlarged end such as 19, which projects into the chamber 18 and is retained therein by reason of its bearing against the shoulder 17. A stud 22 is provided with an enlarged base 21 extending also into the chamber 18 and retained therein by means of the base 21 engaging the shoulder 23 of the chamber 18, and a spring 20 is interposed between the portions 17 and 21 to hold them in firm seating position with the portions of the chamber 18 against which their enlarged ends bear.

Conversely extending openings 24 and 25, 75 running parallel one to the other, are provided through the insulator 7 and 7', having between them a partition 26.

A switch member having operating buttons 29 and 35 provided with enlarged plugs 80 29' and 35', is provided and includes a rod 30 having a screw threaded end 30" serving to engage the member 35 thereto, which rod 30 is provided with an offset portion 30' and a straight end portion 32. Below the rod 30 85 is a shorter rod 31 provided with an inclined end portion 31'. It would of course be understood that these rods are formed of some good electrical conducting material. The rod 30 is adapted to be housed by the opening 24, while the rod 31 projects into the opening 25.

In operation it will be noted that the current, assuming that a bulb is positioned within the socket and that the switch member is in the position shown in Fig. 4, will come down through wire 11 and through screw 9 into the rod 30 at 30' and bridge across by means of the conductor 32 to the rod 31 which firmly engages the stud 22, thence 100 through the spring 20 to the contacting member 16, through the filament of the lamp and in return to the member 6 to the contact member 14 through the neck 12 of the same and back into the wire 15. It will be noted that when the switch is open, as shown in Fig. 5, which is accomplished by pressing the member 35, there will be two gaps in the circuit, as for instance, between the screw 9 and the rod 30 and the rod 31 and the stud 22, which will make it impossible for the current to bridge and thus the circuit will 110

be retained opened, until it is desired to light the lamp when the circuit may be closed by exerting pressure upon the button 29.

Having described my invention, what I claim is:

1. A light socket including a casing having oppositely arranged openings, an insulating plug in the casing having spaced transverse openings extending to the openings in the casing, contact points extending into the openings of the plug, buttons arranged for sliding movement in the openings in the casing, a conductor rod connecting said buttons and arranged in one of the 10 openings in the plug and for engagement with one of the contact points, and a shorter rod attached to one of the buttons and arranged in the other opening in the plug and for engagement and disengagement with the 15 other contact point, said rods being electrically connected together.
2. A light socket including a casing having oppositely arranged openings, an insu-

lating plug in the casing having spaced transverse openings extending to the openings in the casing, contact points extending into the openings of the plug, buttons arranged for sliding movement in the openings in the casing, a conductor rod connecting said buttons, arranged in one of the openings 25 in the plug and having an offset portion for engagement with one of the contact points, and a shorter rod attached to one of the buttons and arranged in the other opening in the plug and for engagement and disengagement with the other contact point, the last named contact point being spring 30 pressed and said rods being electrically connected together.

In testimony whereof I affix my signature 35 in presence of two witnesses.

VICTORINO MARTINEZ.

Witnesses:

CARLOS INOGUERAL,
H. C. VOGENITZ.
